J. DANUBIO

HAIR PROTECTOR AND CONFORMER

Filed Dec. 14, 1922

UNITED STATES PATENT OFFICE.

JOSEPH DANUBIO, OF EAST WEYMOUTH, MASSACHUSETTS.

HAIR PROTECTOR AND CONFORMER.

Application filed December 14, 1922. Serial No. 606,899.

To all whom it may concern:

Be it known that I, JOSEPH DANUBIO, a citizen of the United States, residing at East Weymouth, in the county of Norfolk and 5 State of Massachusetts, have invented certain new and useful Improvements in Hair Protectors and Conformers, of which the following is a specification.

This invention relates to hair protectors 10 and conformers and has for its principal object the provision of a light covering for the head of net or other reticulated construction closely fitting the hair for the protection of the same at the time of retiring and designed 15 also for day-time wear in the case of athletes or others who may be caused annoyance in the course of their employment by hair falling into the eyes.

Another object of the invention is the construction of a hair protector and conformer 20 held in place by a band encircling the head and secured thereto by slight elastic pressure, said band being sufficiently broad in its forward part to distribute said pressure 25 over a wide area of the forehead to avoid after-marks on the forehead indicating previous use of the device.

Still another object of the invention is the construction of a hair protector and conformer 30 with a head embracing band divided at the rear and adjustably fastened together to provide for change of size, the fastening means being arranged to one side of the median line of the head to prevent discomfort which might otherwise be suffered by 35 the wearer of the hair protector in lying upon said fastening means.

A further object of the invention is the provision of a band with an inelastic edge 40 adjacent the net or reticulated part of the device the free edge of said band being formed with an elastic portion.

With the above and other objects in view, my invention consists in the improved hair 45 protector and conformer illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is 55 illustrated:

Figure 1 is a perspective view of my improved hair protector and conformer viewed from the rear.

Figure 2 is a perspective view of one form 60 of hair protector and conformer applied to the person of a wearer.

Figure 3 is a similar view of a slightly modified form of the invention.

Figure 4 is a detailed view of the fastening means. 65

Figure 5 is a section taken along the line 5-5 of Figure 4.

Referring now in detail to the several figures, the numeral 1 represents a bag-shaped hair covering made from net or other light 70 reticulated material, the lower edge of which is secured in any suitable manner, as by sewing to the upper edge of the band 2. In its preferred form, said band is made from a strip of inelastic material and is adapted to 75 surround the head of the wearer as shown in Figures 2 and 3. In Figure 2 which represents a hair protector and conformer intended for men's use the band is relatively short and intended to encircle the back of 80 the head in a plane not far below the top of the ear as shown in Figure 2. In Figure 3 which illustrates a form of the invention designed for women's use the band 2 is made somewhat longer so as to embrace the head 85 rather low down in the back for the purpose of accommodating the rather abundant quantity of hair which usually characterizes a woman's head adornment. In this case the net or reticulated portion of the hair protector is necessarily larger.

The band 2 is divided at the back as clearly shown in Figure 1 and the line of division is carried upwardly a short distance into the net portion as shown at 3 in Figure 95 1, the cut edges 4 of the net being bound as shown. The free ends 5 and 6 of the band are of sufficient length to overlap as illustrated in Figure 4 one of said ends being provided with a slot 7 through which protrudes the other end, said ends being detachably fastened to the adjacent portions of the band by means of the snap fasteners 8. In order to provide for variations in the size of the band 2 several snap fasteners are provided on each side, to any of which the free ends 5 and 6 may be secured. 100

Said snap fasteners afford a step by step adjustment in the size of the hair protector and conformer, and to provide a flexible 110

adjustment in size between said steps, the lower edge of the band is furnished rearwardly with an elastic portion 9 on each side imparting to the band a slight elastic pressure which holds it in snug conformation to the head of the wearer. The elasticity is confined to the lower free edge of the band 2, the upper edge of said band being inelastic and invariable in length. It is to 10 this upper edge that the reticulated portion of the device is secured and were said upper edge elastic the adjacent meshes of the reticulated portion would be drawn together upon contraction of the band entrapping loose hairs and pulling the latter much to the discomfort of the wearer.

The band 2 is made sufficiently broad where it bears upon the forehead to distribute the pressure of the elastic portion 9 over a great area of the forehead so as to insure that no after-marks will be left upon the forehead through pressure of the band which would indicate previous use of the device. The band is preferably positioned 25 a short distance above the eyebrows as shown in Figures 2 and 3 and may be slightly narrowed or cut away as at 10 where it passes over the ears.

My improved hair protector and conformer is adapted for either day or night 30 time wear. Its particular function at night time is to hold the hair in the position in which it may have been brushed or combed prior to retiring without the risk of it becoming disarranged or mussed due to tossing of the head while asleep. It is particularly designed for men whose hair is hard to train or who wish to change the style of arranging the hair, as it holds the hair in set 35 position against inadvertent displacement until it has become set to lie naturally in the desired manner. The hair protector and conformer opens in the rear for the purpose of enabling the application of the 40 same to the hair without deranging the same after it has been combed. It may also be used with advantage by women who wish to curl the hair and in the case of those who wear the hair bobbed it will be especially 45 efficacious in holding the locks in place.

By preserving the hair unmussed, the hair

protector and conformer prevents its being pulled out when combed.

As a day-time article of apparel my improved hair protector and conformer is intended to be used particularly by athletes or those who engage in strenuous games such as tennis or any work of violent character in which the hair is apt to fall into the eyes. The hair protector not only holds the hair 60 in place but the band serves as a sweat band eliminating the discomfort of having perspiration running down into the eyes. For day-time use the hair protector and conformer is best made with the band 2 considerably narrower than that shown in the drawings, but for night wear a protector with a wide band is contemplated, as a narrow band would have a tendency to be displaced or to leave an after-mark.

Although I have thus described the preferred embodiment of my invention, it is evident that those skilled in the arts to which this relates may make various changes in the construction, combination and arrangement of the several parts without departing from the spirit and scope of the invention.

Having described my invention what I claim as new and desire to secure by Letters 80 Patent is:—

1. A hair protector and conformer comprising a head encircling band inelastic adjacent the upper edge and having a lower elastic portion, and a hair protecting member secured to said upper edge.

2. A hair protector and conformer comprising a head encircling band inelastic adjacent the upper edge and having a lower elastic portion, and a reticulated hair protecting member secured to said upper edge.

3. A hair protector and conformer comprising a head encircling band inelastic adjacent the upper edge and having an inelastic forehead-engaging portion, a reticulated hair protecting and conforming member secured to said upper edge, the lower edge of said band being elastic rearwardly of said forehead-engaging portion.

In testimony whereof I have hereunto set my hand.

JOSEPH DANUBIO
